HYDROTHERAPY UNIT

Samuel L. McNair, Overland Park, Kans., assignor to
The Songrand Corporation

Filed Dec. 14, 1970, Ser. No. 26,486

Term of patent 14 years

Int. Cl. D24—01, 99

U.S. Cl. D83—1

Fig. 1.

Fig. 2.

Fig. 3.

FIG. 1 is a top plan view of a hydrotherapy unit showing my new design;

FIG. 2 is a bottom plan view thereof;

FIG. 3 is a side elevational view thereof showing one side;

FIG. 4 is a side elevational view thereof showing the other side;

FIG. 5 is an end elevational view taken from the right hand end of FIG. 4;

FIG. 6 is an end elevational view taken from the left hand end of FIG. 4; and

FIG. 7 is a fragmentary sectional view taken along line 7-7 of FIG. 3 in the direction of the arrows.

I claim:

The ornamental design for a hydrotherapy unit, as shown.
